United States Patent Office.

PH. J. PROBECK AND JOHN B. CORLETT, OF NEWBURG, OHIO.

Letters Patent No. 90,124, dated May 18, 1869.

IMPROVED INVALID-TABLE AND BOOK-HOLDER.

The Schedule referred to in these Letters Patent and making part of the same.

To all whom it may concern:

Be it known that we, PH. J. PROBECK and JOHN B. CORLETT, of Newburg, in the county of Cuyahoga, and State of Ohio, have invented a certain new and improved Invalid-Table and Book-Holder combined; and we do hereby declare that the following is a full and complete description of the same, reference being had to the accompanying drawings, making part of this specification, in which—

Figure 1 is a side view of the apparatus while in use.

Figure 2, a detached view of the table.

Figure 3, a side view of the table.

Figures 4 and 5, detached views of the book-holder.

Like letters of reference refer to like parts in the different views presented.

The nature of this invention relates to an adjustable table, in combination with a book-holder, the two being so arranged, and in such relation to a bed, that a person lying therein can easily and conveniently hold a book or paper, for reading, or make use of the table, on which to place any needful article.

In fig. 1, A represents the bed, which is or may be of the ordinary description.

To the side of said bed, is secured, in a sleeve, B, a standard, C, whereby the table D is supported by means of the arm E. Said arm is so attached to the standard, that it can be turned round horizontally, thereby allowing the arm, and the table thereto attached, to be brought to any position that a person, lying in the bed, may require.

The table may also be elevated, more or less, above the bed, by raising or lowering the standard in the sleeve, and in which the standard is secured by the finger-screw F.

On the opposite end of the arm is secured a tray, H, which may be adjusted on the arm at any partic-

ular point, or removed therefrom, as may be necessary.

Fig. 4 represents the book-rest or holder. Said rest consists of three or more light frames, I, hinged to each other, whereby they may be folded up, or made to assume variable angles, as the book or paper may require.

The lower frame, I', serves as a stand, for the support of the two or more upper frames, when placed upon the table for practical use, as shown in fig. 1, in which it will be seen that the upper frames serve as a back, against which the book inclines, while the bottom of the same rests upon the lower frame or stand I'.

The upper rail of the frame is provided with a hook, a, on which a newspaper may be hung when spread out on the frame, and thereby held in proper position for reading.

The frame, when not needed, is easily removed from the table, folded up into a small compass, to be laid aside for future use.

This apparatus is neat in appearance, of simple structure, and of easy adjustment, requiring but a few minutes to attach it to the bed, or to remove it therefrom. It is of great convenience to the invalid, and readily accessible to his reach.

What we claim as our invention, and desire to secure by Letters Patent, is—

The combination of the jointed frame or book-holder I, pivoted arm E, table D, tray H, and adjustable standard C, all arranged and constructed to operate in the manner and for the purpose substantially as described.

PH. J. PROBECK.
JOHN B. CORLETT.
